UNITED STATES PATENT OFFICE.

BYRON B. GOLDSMITH, OF NEW YORK, N. Y.

DESIGN FOR A TELESCOPING COVER FOR PACKING AND DISPLAY BOXES.

SPECIFICATION forming part of Design No. 35,512, dated December 31, 1901.

Application filed April 23, 1901. Serial No. 57,141. Term of patent 14 years.

To all whom it may concern:

Be it known that I, BYRON B. GOLDSMITH, a citizen of the United States, and a resident of the city, county, and State of New York, 5 have invented a new and original Design for a Telescoping Cover for a Packing and Display Box, of which the following is a specification.

The drawing represents the cover of the box 10 in perspective.

The leading feature of the design consists in a telescopic cover A, having a band B at one end carrying a frame-like ornamentation surrounding a space usable for an advertisement, a diagonal band C, carrying an ornamentation shown in the shape of an embossed tie or knot, and a band D at the end removed 15

from the band B, also carrying an ornamentation in the shape of a frame, but having the part within the frame cut away and removed, 20 so as to show the part of the article displayed, which is found underneath.

What I claim is—

The design for a telescoping cover for a packing and display box for lead-pencils and similar articles substantially as herein shown and described. 25

In testimony whereof I have signed my name to this specification in the presence of two subscribing witnesses.

BYRON B. GOLDSMITH.
